UNITED STATES PATENT OFFICE.

WILLIAM A. HASTINGS AND MILES C. GERALD, OF THORNDIKE, MASS.

IMPROVEMENT IN LOOM SHUTTLE-GUIDES.

Specification forming part of Letters Patent No. **151,487**, dated June 2, 1874; application filed May 19, 1873.

To all whom it may concern:

Be it known that we, WILLIAM A. HASTINGS and MILES C. GERALD, of Thorndike, State of Massachusetts, have invented a Movable Shuttle-Guide for Looms, of which the following is a specification:

The object of our invention is to provide a loom with a movable shuttle-guide, which is moved automatically by the movement of the loom, or a portion of it, and which moves away from the lathe, and is in proper position to serve as a guide to the shuttle while the latter is passing through the shed from one box to the other; but which, when the shuttle is in its box at either end of the lathe, is moved in against or near to the lathe, so that it may be out of the way of the operator while adjusting threads or other matters about the loom; all of which movement is accomplished by means of a crank-rod extending from the shaft to some part of the lathe, to which rod is loosely attached another rod pivoted to the lathe, a part of which, extended to the front of the lathe, forms the shuttle-guide, so that the vertical movement of the crank-rod gives a horizontal or nearly horizontal movement of that part of the rod forming the shuttle-guide, as will be hereinafter explained.

In the drawings, Figure 1 is a perspective view, illustrating my invention and its application to a loom; and Fig. 2 is a vertical section of the same.

A represents the ordinary lathe, consisting of the uprights D D, pivoted at their lower ends, and provided with the beam e and hand-rail e, with the reed i secured between; and l is the crank-shaft, which gives motion to the lathe upon its pivots by means of the rods g g, extending from the cranks of the shaft l to the lathe. The reed is omitted in the drawing in Fig. 1, in order to show more clearly the application of the shuttle-guide to

the lathe. The guide a extends along the front of the lathe, from one end of the reed to the other, and is bent back between the beam e and hand-rail e, past the ends of the reed, and downward, forming the arms a', which are pivoted to any suitable part of the lathe, as to the uprights D D, by passing around the rod f, and are connected to the rods g by an arm, h, at one or both ends of the loom, so that as the crank-shaft l is rotated, the arm h is given a vertical movement, imparting a lateral motion to the rod a, to and from the reed; and when the cranks s s are up and in a vertical position, as shown in Fig. 2, the rod a is in its extreme outward position in front of the reed, to operate as a guide to the shuttle as it passes through the shed from one box to the other, and preventing it from flying out; but when the cranks s s are down, the rod a is in a position close to the reed, out of the way of the operator, when adjusting broken threads, &c., and the rod a is moved from one position to the other, as above described, by the ordinary movements of the loom.

It is evident that other ordinary pivots might be used instead of the rod f, extending from one upright, D, to the other, as shown in the drawing.

What we claim as new, and desire to secure by Letters Patent, is—

The combination of crank-shaft l s, connecting-rods g, bent rod a h, and vibrating lathe A, the connecting-rods being so arranged as to operate the rod a through one or more arms, h, and rock the lathe at the same time, substantially as shown and described.

WILLIAM A. HASTINGS.
MILES C. GERALD.
